SHEET-SETTLING CONTROL

Frank Casper, Cleveland, Ohio, assignor to Kenneth H. Kolpken, Cleveland, Ohio

Application July 17, 1947, Serial No. 761,596

3 Claims. (Cl. 271—60)

1

My invention pertains to a sheet-settling control by use of a backstop appliance intended to furnish a guiding and alining conformation, especially for the rear part of a sheet of paper being delivered thereover to the transfer table of a vertical-type printing press, along the rear edge of which transfer board one or more of my backstops of improved design are fixedly or detachably and adjustably mounted.

Long experience (over four decades) in the printing industry brought me familiarity with the tendency occasionally of some sheet, due to unevenness in the size of the pre-cut sheets, to become disaligned during passage from the top of a stack of sheets to the transfer board which has a compound movement imparted thereto. One of the earliest attempts at correction was the provision of upstanding tacks along the rear of a wooden transfer table. Currently, there is being marketed an attachment to the rear of the transfer board which consists of a member provided with a pair of laterally spaced and right-angular and forwardly projecting smooth flanges occupying the same horizontal plane and underneath which the rear edge of each sheet is intended to slip to become prevented from upward displacement. However, that intention is not invariably realized in practice because such flanges do not reliably cause an upwardly curled rear edge of a sheet to slip underneath the flanges to become held therebelow. Besides my observation of earlier accessory devices, for a like purpose, on presses in use, I have investigated patents of class 271, sub-class 60 without alteration of my conviction that my origination is superior and in consequence of demonstrated advantages is worthy as the subject matter of a patent contract.

Accordingly, the object of my invention is to provide an appliance serving to correct a non-uniform pick-off of the uppermost sheet from the stack, also, automatically (with the aid of gravity and an attendant air current) to correct for curling or buckling of the rear part of a sheet and to realine any which may have its rear edge oblique and consequently with a section thereof unrestrained during its transfer preparatory to receiving its inked impression.

While the form hitherto employed (Figures 1 to 3) comprised a pair of adjustably attachable backstops, each about one and one-half inches wide, which have been learned to be adequate when spaced apart laterally several inches (four or more) measured middle to middle, such dimensions may be varied to suit or to be most effective for the size of the sheets to be drawn thereover.

2

We may conclude to have them become a fixed or even integral, upstanding part of the rear edge of the transfer board.

The now preferred design of the forward face of each backstop establishes it to form an angle of about eighty degrees from the horizontal, measured between such forward face and its rearwardly extending bottom; and to have it comprise a plurality (five being illustrated) of zig-zag sections between a vertical, lower section and an upper section which predeterminedly recedes in a downward direction from its upper, forward edge. Longer use may cause adoption of some modification in the "corrugated" interception surface.

It is therefore to be realized that the scope of my invention comprehends many equivalent constructions and that the graphical disclosures together with the following specific descriptions are merely exemplifications of features of design or of other feasible mechanical embodiments and arrangements within the scope of the granted claims.

Adverting to the drawings:

25 Figure 1 is a perspective (broken) view of the parts of a vertical-type printing press essential to an understanding of coaction therewith of backstops embodying the principles of my invention.

20 Figure 2 is an enlarged top plan view of a plate adjustably carried by the transfer board, the said plate in turn adjustably carrying a pair of backstops embodying my invention.

30 Figure 3 is a still further enlarged end view of one backstop and its mounting.

35 Figure 4 is a rear elevation of Figure 2.

Figure 5 is a modification in respect to two features.

Because vertical-type presses are now well known to printers, the parts and mechanisms which border three sides of the transfer board have been illustrated as a broken view in Figure 1, but the following description need identify only a few of the cooperating parts to evidence their 40 relative locations in aid of an understanding of the improving function exercised by my originated structure.

A chase frame 1 on which a type-carrier and cylinder (not shown) reciprocate periodically in 45 opposite directions so that the latter rolls against the former. A stack of sheets to be printed is indicated at 2 and extending diagonally therebelow is the conventionally swingable sheet delivery mechanism 3 for drawing one sheet at a time across the transfer table 4 and in a direc-

tion toward the printing couple. The rear part of the transfer board 4 adjustably carries, as hitherto, a plate 5 having the common slot parallel with the direction of travel of the sheets thereover and with which slot a set screw (not shown) cooperates for fixing the plate in the desired position of adjustment.

In laterally spaced relationship, as exemplified, are a pair of upstanding flanges 6 along the rear of the plate 5. On each of the flanges 6 there is shown to be mounted one of my backstops of advantageously unique design, comprising; a member 7 provided with a channel 8 open below and closed above which is adapted to straddle and to be loosely occupied by one of the flanges 6 preparatory to being fixed in a selected position by a set screw 9, as appears to view in all of Figures 2 to 4 inclusive.

Consideration of the enlargement of Figure 3 is invited for observation of the zig-zag conformation of the forward face of each backstop when viewed as a cross-section or parallel to the direction of travel of a sheet thereover and which forward faces are to guide and to reposition the released sheets. The mean obliquity of each forward face is such as to form an acute angle of about eighty degrees, measured rearwardly to the plane of the transfer board. The zig-zag or step-like face comprises a lowermost and substantially vertical section area 10, then progressing upwardly further comprises five meeting section areas 11 of alternately different obliquity yet collectively receding in an upward direction with respect to a plane normal to the forward part of the transfer table, the lower one extending rearwardly and upwardly and the upper one extending, as does the middle one, substantially parallel with the lower one. The other two will be seen to extend forwardly and upwardly. The uppermost section area 12 recedes somewhat more steeply in a downward direction starting right at the front, upper corner of each backstop, whereby, immediately after the rear edge of any sheet, during its transfer, has passed such upper, front corner it may slip below the section area 12 and thereafter be provisionally or initially restrained thereby from any upward movement. While settling further, the rear edge or rear portion of the sheet slips successively over the three lower apexes and finally along the vertical section area 10.

In operation, the sheet delivery 3 lifts a sheet from the stack 2, draws it over the transfer board 4 and deposits it thereon while the edge of the board which is furthest from the printing couple is lower than the board edge which is nearest to the printing couple which are movable in the chase frame 1. The trailing edge of the sheet settles over the here featured forwardly presented face of the backstop 7 without curling or buckling and in substantial alignment with the section area 10. Thereafter, the board 4 descends and simultaneously becomes reverse tilted to the position in which it appears in Figure 1, preparatory to permitting each sheet to slide off toward the conventional grippers of one part of the printing couple.

The double modification of Figure 5 consists, first, in having a transfer board 13 integrally carry along its rear one or more of aligned back-

stops 14 featuring my concept by comprising the lower, vertical section area 15, the upper section area 16 and fewer and finer intermediary section area 17 which simulate saw teeth in design.

In operation, after a sheet has been drawn across the backstops on the transfer table preparatory to the desirable settling upon the latter, its rear edge, whether warped or oblique to its side edges or even slightly curled, will readily sink along the components 12 of the forward faces of the backstops and any tendency of a sheet's rear edge to rise will be frictionally resisted. Thereafter, the rear part of each sheet continues its slow, wave-like settling over the gentle slope components 11 and in so doing the action of gravity will tend to effect a leveling of opposite lateral edges and incidentally cause the sheet slightly to turn during its deposition along the steeply inclined forward faces so as to bring the rear edge of any unevenly cut sheet more nearly into parallelism with the mean plane of the forward faces of the two or more backstops. Finally, the vertical components 10 will allow unimpeded, last-stage deposition so that the rear edge of the sheet is in abutment with the component surfaces 10. Important it is that the rear edge of the sheet, after passage over the tops of the backstops, immediately slips rearwardly past the tops of the slope components 12 and thereafter is continuously restrained from any relative rise during the bodily descent of the entire sheet.

I claim:

1. In a sheet-settling control for a printing press of the vertical type to comprise a printing couple, a sheet-stack support, therebetween a transfer board adapted to tilt to reversed obliquity from horizontal while being bodily raised and lowered and sheet conveying means both to and from said board; an upstanding backstop structure along the rear border of the transfer board, the forwardly directed face of said backstop simulating a step-like formation and in its entirety receding upwardly from a plane normal at its forward line of intersection with the board as well as during conveyance of a sheet thereover.
2. An appliance as in claim 1, there being a plurality of upstanding flanges carried by the board and arranged crosswise of the path of sheet travel and backstops adjustably connected with said flanges respectively.
3. A control as in claim 1, the zig-zag face comprising a lowermost sectional area which is substantially normal to the board and an uppermost sectional area which recedes from its upper edge.
